UNITED STATES PATENT OFFICE.

ROBERT ELWOOD DUFFY, OF TORONTO, ONTARIO, CANADA.

OIL-BURNER.

1,318,136.

Specification of Letters Patent.

Patented Oct. 7, 1919.

Application filed January 3, 1919. Serial No. 269,493.

To all whom it may concern:

Be it known that I, ROBERT ELWOOD DUFFY, a subject of the King of Great Britain, of the city of Toronto, county of York, Province of Ontario, Dominion of Canada, have invented certain new and useful Improvements in Oil-Burners, of which the following is a specification.

My invention relates to improvements in oil-burners, and relates more particularly to that class of oil-burner wherein a suitable fuel is transformed into gas, and one of the objects of my invention is to make a generator, in the preferred construction of my invention, of aluminum, so as to avoid scaling thereof which occurs when steel or iron is used, with the result that the orifices in the generator-burner located beneath the generator are considerably clogged up. Since aluminum will not scale, I derive the great advantage of always keeping the orifices in the generator-burner clean. Another object of my invention is to improve the construction of air-mixing chambers so as to permit the same to be readily assembled and taken apart, and to enable a positive supply of air to be provided therefor, which supply of air is taken into the mixing-chamber well below the generator-burner.

Other objects of my invention will appear in the following specification.

Figure 1 is a side elevation of a gas-burner within my invention, certain parts being shown in section. Fig. 2 is a side elevation of my burner at right angles to Fig. 1, parts of the generator-burner and generator being shown in vertical longitudinal section, as well as certain connecting parts. Fig. 3 is a vertical cross section, on an enlarged scale, on the line 3—3, Fig. 2, and Fig. 4 is a detail partly in section of a self-cleaning needle-valve mounted at the gas-discharge end of the generator. In the drawings, like characters of reference refer to the same parts.

It is well-known that changes in the atmosphere affect very materially the draft through the flues with which the fire-box of a stove is connected, and it is also well-known that the flame issuing from the gas-burner, as well as from the generator-burner, consumes a great deal of air, and, therefore, it is very important that the air-intake orifices of the mixing-chamber be positioned well below the generator-burner so

as to insure a proper supply of air into the mixing chamber in order to provide for proper combustion.

A is the gas-burner, supported by a hollow member or manifold B, suitably coupled thereto and communicating with the interior thereof. Tapped into one side of the hollow member B, as shown at C, is a gas pipe D. E is a generator-burner, of any suitable construction, and the same is coupled to the hollow member B, through the medium of any suitable means such as the plate F, forming part of said hollow member, and screws G, or other fastening means, held in said plate. H is the generator, located above the generator-burner E. The fuel enters into the valve-casing I, through the conduit J, and the escape of said fuel from the inner end K of the valve-casing I into the generator H is regulated in a well-known manner by the valve-stem L. Although the fuel is fed from a pressure tank (not shown), of course any suitable method may be employed to feed fuel to the burner. The inner end K of the valve-casing I is coupled to one end of the generator H and the nipple 3 is coupled to the other end of said generator. The extension 4 of the valve-casing 5 screws into the outer end of the nipple 3. The upper end of the pipe D projects through an opening 6 into the chamber 7 of the air-supply device. This chamber is made of an upper portion or cap 8 and a lower portion 9, suitably coupled together as by screws 10. In the back of the chamber 7 is formed an opening 11, through which extends the outer end of the nipple 3. The air-supply device, supported by the pipe D, provides a positive means for supporting the vertically disposed portion of the gas-discharge end of the generator. When the valve-casing 5 has been coupled to the nipple 3, the valve-stem 12 operating in the valve-casing 5 is removed, and then the upper portion or cap 8 of the chamber 7 is placed in position, after which the valve-stem 12 is replaced.

An arm 13, carried by the generator-burner E, supports at its upper end 14, the valve-casing I, by means of the shoulder 15 of said casing resting against said upper end. The nut 16 screwing on the threaded portion 17 of the valve-casing I holds the said valve-casing snugly in place and provides a convenient means for supporting the fuel-receiving end of the generator.

As is usual in gas-burners, a pan or saucer is employed to generate sufficient gas from fuel to make the burner automatic in its action. I prefer to form the pan integrally with the same casting comprising the generator-burner E, as shown at 18. So soon as the fuel within the pan 18 heats the generator H sufficient, the fuel passing thereto from the conduit J becomes gasified and escapes through the orifice 19, formed in the valve-casing 5, and since air is supplied to the air-supply device by any suitable means such as the tubular inlets 21, the gas passing into the pipe D becomes mixed with the proper proportion of air, and escapes through the openings a and b, formed respectively in the hollow member B and the bottom of the generator-burner E and plays upon the generator H. Simultaneously, gas passes from the pipe D into the hollow member B and divides, passing through the arms c into the gas-burner A.

It will be seen upon referring particularly to Fig. 2 that the intake ends of the tubular inlets 21 are positioned well below the generator-burner, and, therefore, I am assured of a proper supply of air into the mixing-chamber.

A portion d of the generator-burner E is not provided with orifices, this providing, in effect, a baffle plate, which compels the dispersal of the gas into each end of the generator-burner.

It is very important that the waste products of combustion that will not permit perfect combustion in the gas-burner A, be removed from the gas before it reaches this burner. I have found from experiments that a core or filling e made of suitable mineral such as asbestos or aluminum shavings most admirably performs the function required. This mineral core or filling possesses sufficient porosity to permit free passage of oil into the generator and the free escape of gas therefrom. By reason of its nature, the said mineral core or filling becomes greatly heated and absolutely insures the fuel escaping in the form of gas from the generator H.

50 A wire f is preferably passed through said core or filling so as to permit the same to be readily placed and removed.

If desired, the screens g may be mounted within said generator beyond each end of the core or filling.

Although I may use any suitable material in making the generator H, I prefer to use aluminum, or its equivalent, from the fact that by my experiments I have found that such a generator heats very much more quickly than generators made of iron or steel, and possesses a considerable advantage.

Some suitable means must be employed to support the burner, and a suitable means 65 illustrated comprises a circular stand O

slotted where necessary to permit the burner to be placed therewithin. To provide for the supply of air, said stand is provided with openings o.

From the foregoing specification, it will be understood that the various parts of my burner may be readily taken apart for cleaning purposes, or for repairs.

In time, the orifice 19 of the valve-casing 5 will become more or less clogged unless some means is provided to readily clean said orifice, and this means should be of such a nature as to render it unnecessary to put the burner out. For the purpose of cleaning the orifice, I provide the valve-stem 12 with a pin 20 in alignment in said orifice. When manipulating the valve-stem 12, the said orifice can be kept readily cleaned.

Opening into the chamber 7 of the air-supply device is a hole 1, which co-acts with the tubular inlets 21 to supply air.

I find that if I make the wire f of aluminum, this heats up much quicker than when made of iron or steel, with resultant advantages.

Various changes in construction may be made in that disclosed without departing from the spirit of my invention. For example, though I have described both arms c of the hollow member B as conducting gas into the gas-burner A, really only one of these arms may be used for that purpose.

Claims.

1. The combination of a substantially circular stand having air inlet openings and provided with vertical slots downwardly from the upper edge thereof, a horizontally disposed tubular loop burner supported on the upper edge of said stand, a depending manifold having arms connected to opposite sides of said burner, an air supply device having a chamber, a vertically disposed valve in said chamber, a generator tube located below said burner between the arms of said manifold and having one end projecting into said chamber and connected to said valve, an L-shaped conduit connecting the bottom of said air supply device with said manifold, a generator burner supported between the arms of said manifold below said generator, a fuel supply controlling valve connected to the other end of said generator tube, an arm carried by said generator burner supporting the last named valve, and a connection between said manifold and the generator burner, the ends of said generator and said arm being removably disposed within the slots of said stand.

2. The combination of a horizontally disposed tubular loop burner, a depending manifold having arms connected to opposite sides of said burner, an air supply device having a chamber, a vertically disposed valve in said chamber, a generator tube located below said burner between the arms of said

- manifold and having one end projecting into said chamber and connected to said valve, an L-shaped conduit connecting the bottom of said air supply device with said manifold, 5 a generator burner supported between the arms of said manifold below said generator, a fuel supply controlling valve connected to the other end of said generator tube, an arm carried by said generator burner supporting the last named valve, and a connection between said manifold and generator burner.
3. The combination of a horizontally disposed tubular loop burner, a depending 15 manifold having arms connected to opposite sides of the burner, an air supply device having a chamber, said air supply device including a lower member with depending air inlets at the opposite ends of the bottom 20 thereof and a removable cap secured on said lower member, a vertically disposed valve in said chamber, a generator tube located below said burner between the arms of said manifold and having one end projecting 25 into said chamber and connected to said valve, an L-shaped conduit connecting the bottom of said air supply device with said manifold, a generator burner supported between the arms of said manifold below said generator, a fuel supply controlling valve connected to the other end of said generator tube and a connection between said manifold and the generator burner. 30
4. The combination of a horizontally disposed tubular loop burner, a depending 35 manifold having arms connected to opposite sides of said burner, an air supply device having a chamber, a vertically disposed valve in said chamber, a generator tube located below said burner between the arms 40 of said manifold and having one end projecting into said chamber and connected to said valve, an L-shaped conduit connecting the bottom of said air supply device with said manifold, a generator burner supported 45 between the arms of said manifold below said generator, a fuel supply controlling valve connected to the other end of said generator tube, and a connection between said manifold and generator burner.

ROBERT ELWOOD DUFFY.
